UNITED STATES PATENT OFFICE.

JOSEPH C. BROWN, OF CLARK, WYOMING.

GUARD-FINGER.

1,270,689.

Specification of Letters Patent. Patented June 25, 1918.

Application filed December 1, 1917. Serial No. 204,859.

To all whom it may concern:

Be it known that I, JOSEPH C. BROWN, a citizen of the United States, residing at Clark, in the county of Park and State of Wyoming, have invented certain new and useful Improvements in Guard-Fingers, of which the following is a specification.

This invention is a wearing or spacing member more particularly adapted for use 10 in connection with guard fingers wherein the arms projecting laterally from the fingers are formed to have a sector shape in cross section and mounting thereon a bushing to serve as a wearing and spacing 15 member.

The principal object of the invention is to provide a wearing and spacing member that may be readily applied to the lateral arms of guard fingers, which member will 20 prevent excessive vibration but no independent movement sufficient to break the individual finger shanks or loosen their connection with the finger bar.

Another object of the invention is to provide 25 a member that is simple and strong in construction, formed of suitable material and one that will be cheap to manufacture for quick and easy renewal.

Broadly stated, the invention comprises a 30 wearing and spacing member that is sector shape in cross section and provided with a similarly shaped bore extending longitudinally therethrough, said member having its ends adapted to engage with the guard 35 fingers, and the bore in said member being adapted to receive the lateral arms extending from said fingers.

One practical form of construction and 40 assembly will be described and illustrated in the accompanying drawings, in which:

Figure 1 is a top plan view of four guard fingers assembled and between two of said fingers the member is shown in section and in position on two of the lateral arms,

Fig. 2 is a side elevation partly in section of one of the guard fingers showing the curved recess adjacent the ends of the lateral arm,

Fig. 3 is a sectional view on the line 3—3 50 of Fig. 1, showing the guard finger in side elevation, and

Fig. 4 is a perspective view of the wearing or spacing member.

One practical form of the invention includes the guard fingers generally indicated at 55 5 having the lateral arms indicated at 6

and 7. These arms 6 and 7 are oppositely positioned upon the guard fingers 5. Adjacent the inner ends of these arms 6 and 7 where they join the finger guard, the guard 60 is provided with a curved recess 8 that is substantially sector shaped.

The arms 6 and 7 are also sector shaped. As shown in Fig. 1 the arms do not contact at their ends with each other in the assembly illustrated. To coöperate with these arms 6 and 7 there is provided a wearing and spacing member generally indicated at A.

The wearing and spacing member A is of 70 an elongated form and is approximately sector shape in cross section. As shown it is provided with a flat side 9 that connects with another flat side 10 that is positioned at right angles to the side 9. Each of the 75 sides 9 and 10 are of approximately the same width and they are joined at their other ends by a curved side 11.

In order to mount the wearing and spacing member A upon the sector shaped arms 80 6 and 7 it is provided with a bore 12 that is approximately sector shape in cross section, and the contour follows generally the contour of the member A. As shown in Fig. 3 the bore 12 is positioned nearer the flat side 85 9 so that the material in the member is slightly thinner there than the material between the bore 12 and the side 10, or the bore 12 and the curved side 11.

The wearing and spacing member A serving as a sleeve is preferably sector-shaped so that the flat surface or side 9 will lie in a plane parallel to the cutting blades. This side as shown is approximately flush with the upper surface of the guard finger. 90 95

The under surface 11 is rounded so that the guard fingers will pass smoothly over the stubble left after mowing or cutting. The bore being likewise sector-shaped to coöperate with the arms and this shape of 100 the sleeve and its bore are most effective in retaining the fingers in fixed alinement and to prevent vibration therebetween.

The wearing and spacing member which has been illustrated and described will indicate that the device fills a need when the guard fingers have their arms worn. As soon as the arms get worn it is necessary to aline them and in a short time in use they are displaced. This means that the guard 110 fingers require replacement at more or less frequent intervals. When they become worn

the operation of the machine causes them to jerk sidewise and it is almost impossible to keep them alined.

If these guard fingers be employed upon a grass mowing machine it means that the machine will not cut the grass cleanly and thereby produces a waste that is unnecessary. With this device in use the guard fingers may be kept in proper alinement with little trouble and when they are slightly worn may be easily replaced at small cost.

The guard fingers will not need replacement at such frequent intervals as the member will take up most of the wear. The use of this member will also tend to cause the mowing machine to cut the grass cleanly and thus avoid waste.

What is claimed is:—

1. The combination of guard fingers each having laterally extending arms and provided with a recess formed concentric to the inner end of each arm, a detachable tubular member having a bore therethrough that is sector-shaped in cross-section for receiving adjacent arms and adapting said member to be removably mounted on the arms and interposed between adjacent fingers, said member being approximately sector-shaped in cross-section and serving to retain adjacent fingers in substantially fixed alinement when

assembled on the arms and the end portions of the member are in contact with the walls of their respective recesses to prevent rotative movement between the member and arm and therefrom, independent finger movement.

2. The combination of guard fingers each having laterally extending arms that are approximately sector-shaped in cross-section, a tubular member having a bore therethrough that is substantially sector-shaped in cross-section to permit said member to be removably mounted upon adjacent and alining arms and serving as a wearing and spacing member when interposed between two adjacent guard fingers, said member being approximately sector-shaped in cross-section, and said guard fingers being formed with a recess having a configuration similar to the cross-section of said member for closely receiving the ends of the interposed member and for maintaining them against rotary movement.

In testimony whereof I affix my signature in presence of two witnesses.

JOSEPH C. BROWN.
